ADVERTISING DEVICE

Thomas Charles Fowler, Mount Albert, Auckland,
New Zealand, assignor to Fowler's Automatic
Advertising Limited, Auckland, New Zealand

Application January 9, 1933, Serial No. 650,928,
and in New Zealand February 20, 1932

13 Claims. (Cl. 40—28)

This invention relates to advertising devices of that type employing an endless band carrying information and adapted to be passed behind a sight opening so that said information can be made to appear in the sight opening in such order and for such periods as may be predetermined.

The object of the invention is to provide improved means for operating said endless band, or to fit same in a casing wherein there is mounted 10 a roll of paper, the holder for the latter being geared with the endless band, so that the action of drawing and detaching a section of paper from the roll causes movement of the band behind the sight opening to effect a change in the matter capable of being viewed through said opening.

According to the invention the improved device is characterized by the provision therein of a rocking frame in which a roll of paper is mounted and held against turning movement in said 20 frame, the free end of the paper being left hanging from the device while an endless band carrying matter to be displayed is adapted to be passed behind a sight opening upon movement of the rocking frame in one direction; gearing between 25 said rocking frame and a band driving roller including free wheel mechanism which permits reverse movement of said frame without operating the band driving roller.

Other features are also comprised in the invention which will however, be more particularly described with the aid of the accompanying drawings in which:—

Figure 1 is a perspective view of the complete device

35 Figure 2 a vertical sectional elevation thereof and

Figure 3 a front elevation of the device with the cover or casing and the endless band removed

Figure 4 is a side elevation of the device as it 40 appears in Figure 3

Figure 5 a sectional view of the paper holder and associated mechanism taken on the line A—A, Figure 2,

45 Fig. 5a is an elevational detail partly in section showing the means for securing one of the spindles to the frame,

Figure 6 a detail view showing the ball clutch or free wheel mechanism employed between the 50 paper holder and the gear train,

Figure 7 a detail view showing the return spring associated with the paper holder,

55 Figures 8 and 9, sectional views of the paper holder showing the means for retaining the roll of paper in said holder,

Figure 10 a plan view of the paper holder frame,

Figure 11 a longitudinal section of the sprocket roller for operating the endless band and

Figure 12 a detail view showing the check plate 60 mounted on said sprocket roller.

The device comprises a casing 1 containing a glass closed opening 2, through which advertising matter placed on an endless band 3 is adapted to be displayed, said band passing between the 65 glass which closes said opening 2 and a partition 4 within the casing, there being provided behind said partition 4 a storage space 8 for the band 3 except that portion thereof located between the glass and the partition 4 and the portions of 70 the band 3 adjoining the portion being displayed.

At the bottom of the partition 4 there is mounted a sprocket roller 5 around which the band 3 passes, the latter containing perforations which are engaged by the teeth 5a of the sprocket 75 roller 5, so that when the latter is given turning movement the band 3 is positively driven.

The roller 5 is adapted to be operated, as will be hereinafter described, to draw the band 3 downwards behind the glass closed opening 2, a 80 guide plate 6 leading said band 3 to between the glass and the partition 4, while upon leaving the sprocket roller 5, the band 3 is passed between a curved shield 7 which conforms to the shape of the sprocket roller 5, and a guide plate 8a 85 into the storage space 8, wherein it folds on the bottom 8b to said space, to be ultimately drawn from the top of same, over the guide plate 6 to be repassed between the glass of the sight opening 2 and the partition 4. 90

In order to keep the band 3 properly engaged on the teeth 5a of the sprocket roller 5, there is provided an idle roller 9, which is kept pressed by springs 10 against said roller 5, the band 3 passing between the rollers 5 and 9, the latter of 95 which contains circumferential grooves 9a to take the teeth 5a of the sprocket roller 5.

The sprocket roller 5 is operated intermittently to pass the band 3 downwards behind the sight opening 2, by the action of drawing a length of 100 paper from a roll 11 thereof mounted at the bottom of the device.

The roller 11 has inserted therein a core 11a, having a diamond shaped cross section, the ends of the core 11a being fitted with metal end plates 105 12, and being mounted across a U shaped rocking frame 13, the legs of which are fitted or are attached to and turnable with short spindles 14 journalled in the side walls of the casing 1, while the upper edge of the cross portion of 110

said U shaped frame is provided with serrated cutting edge 13^a. The spindles 14 are short sections of tubing containing opposed slots in their inner ends, into which slots, cross bars or 5 projections 13' on the frame 13 are forced.

One of the spindles 14 has attached thereto the inner end of a coiled spring 15 located within a housing 16, the other or outer end of said spring 15 being secured to said housing or the 10 casing 1.

The other of the spindles 14 has fitted thereon and turnable therewith a ball clutch 17, while surrounding the latter is a toothed wheel 18, which meshes with an idle toothed wheel 19, in 15 turn in mesh with a further toothed wheel 20 on the spindle of the sprocket roller 5.

The balls 21 of the clutch 17 are held in inclined recesses 21^a in the periphery of the latter, so that upon the spindle 14 and clutch 17 being 20 given turning movement in the direction indicated by the arrow in Figure 6 of the drawing, the balls 21 tend to become jammed between the clutch 17 and the toothed wheel 18, and cause the latter to turn with the clutch 17 and the 25 spindle 14. When the clutch 17 is given turning movement in the reverse direction to that indicated by the arrow in Figure 6, there is no tendency for the balls 21 to become jammed between the clutch 17 and wheel 18 and consequently said 30 clutch and its associated spindle 14 are free to turn without the wheel 18. The clutch 17 therefore, provides freewheel mechanism between the frame 13 and the gear train to the band driving roller 5.

35 Means for facilitating the insertion of the core 11^a in, and its removal from the U-shaped frame 13, comprise on the inner side of each leg of the latter, a pivoted plate 22, and a sliding plate 23, containing opposed recesses 22^a and 23^a respectively, which, when said plates are positioned as shown in Figure 9, accommodate and retain an end of the core 11^a.

The frame 13 is slotted to take pins 24 on the plate 23, the latter being normally pressed by a 45 spring 25 towards the plate 22, which upon the plate 23 being moved against its spring 25 and away from the plate 22, is capable of being swung on its pivot to the position shown in Figure 8 to enable a core 11^a to be inserted in or removed 50 from the device, a stop 26 limiting outward movement of the plate 22.

In order to permit only a single revolution at one time of the sprocket roller 5, which is of a diameter such that one turn of said roller will 55 bring about a change of matter on the band 3, to be displayed through the sight opening 2, the sprocket roller 5, has secured to one end a circular plate 27 with a stop 28 thereon, while a bell crank lever 29 carrying a pin 30 at one end 60 is mounted, so that the latter is capable of engagement with said stop 28, the other end of said lever 29 being positioned in the path of travel of a projection 31 from the spindle 14 carrying the clutch 17 and wheel 18.

65 Normally the bell crank lever 29 is held against the action of a spring 32, by the projection 31, so that the pin 30 is clear of the stop 28 but upon the spindle 14 being turned in the direction indicated by the arrow in Figure 4 to cause the projection 31 to clear the end of the lever 29 and following the stop 32 passing from below the pin 30, the latter is by the action of the spring 32 on the lever 29, forced on to the periphery of the circular plate 27, in readiness for engaging 75 the stop 28, when the sprocket roller 5 has made

one complete turn, whereby the travel of the band is stopped. Immediately following the stopping of the band 3, the projection 31 on the spindle 14 again engages the lower end of the bell crank lever 29 and lifts the pin 30 on the upper end of said lever 29 from engagement with the stop 28, leaving the roller 5 free to be given another complete turn per medium of the gear wheels 18, 19, 20 when required.

80 In order to minimize shock likely to be caused by the stop 28 striking the pin 30, there is provided a spring 33 adapted to be engaged by the projection 31 as it comes round to engage the lower end of the bell crank lever 29, thereby 85 bringing the mechanism to a standstill gradually 90 instead of suddenly.

The casing 1 is formed with a downturned upper edge 1^a adapted to be hooked over and behind the upper edge of a back 34, previously secured to a wall or other fixture by screws or other fastenings, so that when the casing 1 is in position on said back 34, the fastenings are hidden and are inaccessible, the lower end of the casing 1 being locked to the back 34 by any suitable means, such as by a pad-lock engaged 100 in a hasp or loop on the back 34 and upon which hasp or loop a slot in the casing 1 is passed.

95 The device is operated as follows:—

The free end of the roll 11 of paper hanging from the bottom of the device as shown in Figures 1 and 2, is gripped and pulled downwards, the operation imparting approximately half a turn to the roll 11 and the U-shaped frame 13 against the action of the spring 15. This brings the cutting edge 13^a of the frame 13 over and 110 into contact with the paper just about where it leaves the roll, so that the unrolled section of paper held in the hand can by being given a twisting or tearing action be detached from the roll 11.

115 When the roll 11 and frame 13 are turned forwards by the pull on the free end of the paper, turning movement is imparted through the clutch 17 and wheels 18, 19 and 20 to the sprocket roller 5, as before described to move the band 3, and effect a change of matter in the sight opening 2.

Following the section of paper being detached from the roll 11, the latter is returned by the spring 15 to the position shown in Figure 2, without operating the wheel 18, inside of which the clutch 17 turns, and upon said return operation being completed, the new end of the paper drops and hangs from the roll 11 in readiness to be gripped for the next operation of the device. 130

I claim:

1. An advertising device comprising a casing containing a sight opening; an endless band carrying matter to be displayed, adapted to be passed behind said opening; a driving roller in 135 engagement with said band; a rocking frame geared with said driving roller; and a roll of paper having its free end hanging from the casing, mounted in said frame so that the action of detaching a section of paper from the roll, moves 140 the frame in one direction and imparts travel to the endless band.

2. An advertising device, according to claim 1, wherein the gearing between the rocking frame and the band driving roller, includes free wheel 145 mechanism whereby said frame is capable of return movement, without operating said driving roller.

3. An advertising device, according to claim 1, wherein the rocking frame is operated to impart 150

- travel to the band, against the action of a spring which returns the paper roll to its normal position, after a section of paper has been detached therefrom.
5. An advertising device according to claim 1, wherein the gearing between the rocking frame and the band driving roller, includes a clutch containing inclined recesses and balls secured on a spindle of said frame, and a toothed gear wheel 10 surrounding said clutch.
5. An advertising device, according to claim 1, wherein the band driving roller is provided with a stop adapted to be engaged by a pin on one end of a spring pressed bell-crank lever, the 15 other end of which is adapted for engagement by a projection on a spindle of the rocking frame, for the purpose set forth.
6. An advertising device according to claim 1, wherein the band driving roller is fitted with a 20 circular plate carrying a stop; a spring pressed bell-crank lever carrying at one end a pin for engaging said stop; a projection on a spindle of the rocking frame for engaging the other end of said bell crank lever and lifting the pins 25 clear of the stop on the circular plate, and a buffer spring adapted to be engaged by said projection, prior to the latter engaging said bell crank lever.
7. An advertising device, as in claim 1, wherein 30 the rocking frame is U-shaped and is provided with a cutting edge adapted to be brought into contact with the paper of the roll, upon the free end of the paper being pulled from said roll.
8. An advertising device, as in claim 1, wherein the rocking frame is U-shaped and the paper roll is mounted on a core detachably held between the legs of said frame.
9. An advertising device as in claim 1, wherein 40 the rocking frame is U-shaped and the paper roll is mounted on a core gripped at each end between plates containing opposed recesses, and adjustable on a leg of said frame.
- 45
10. An advertising device as in claim 1, where- 50 in the rocking frame is U-shaped, and the paper roll is mounted on a core gripped at each end between plates containing opposed recesses, one of said recessed plates being pivoted to the leg 80 of the frame and the other of said plates being 55 slideable on said leg and spring pressed towards the pivoted plate.
11. In an advertising device a rocking frame; a roll of paper mounted therein, and held against turning movement in said frame; a band adapted to be passed behind a sight opening; a gearing between said frame and a band driving roller, whereby movement of said frame in one direction 90 imparts travel to said band.
12. In an advertising device, the parts set forth in claim 11, wherein the rocking frame is U-shaped, and is provided with a cutting edge adapted to be brought into contact with the paper of the roll upon the frame being given movement 95 to impart travel to the band.
13. An advertising device, comprising a casing containing a glass closed sight opening and formed with a down-turned upper edge adapted to be hooked over the upper edge of a back se- 100 cured to a fixture; an endless band carrying matter to be displayed adapted to be passed by a driving roller, between the glass closing said opening and a partition in the casing; a storage space for said endless band behind said parti- 105 tion; a guide plate for said band to the space between said glass and said partition; a shield and a guide plate for said band where it enters said storage space; a rocking frame mounted below said driving roller; a roll of paper mounted 110 in said frame and held against turning movement therein; and gearing between said frame and said band driving roller, whereby movement of said frame in one direction imparts travel to said band.
